UNITED STATES PATENT OFFICE.

FRANK DREW WINKLEY, OF MADISON, WISCONSIN.

IGNITER FOR INTERNAL-COMBUSTION ENGINES.

1,070,649.

Specification of Letters Patent. Patented Aug. 19, 1913.

Application filed July 24, 1912. Serial No. 711,196.

To all whom it may concern:

Be it known that I, FRANK DREW WINKLEY, a citizen of the United States, residing at 524 Francis street, Madison, in the county of Dane and State of Wisconsin, have invented certain new and useful Improvements in Igniters for Internal-Combustion Engines, of which the following is a specification, reference being had

10 to the accompanying drawing.

My invention relates to igniters for internal combustion engines and particularly to igniters of the make-and-break electric spark type, and consists of means whereby 15 the condition of the firing points within the engine cylinder can be determined without removing the igniter; the source of current used for the ignition may be tested by observing a spark produced between external 20 contact points; and the timing of the internal or igniting spark determined without removing the igniter from the engine cylinder.

Figure 1 is an end view of the igniter, embodying my invention. Fig. 2, a view 25 looking down on same.

Like figures of reference denote the same parts wherever they are shown.

For the sake of illustration a well known form of igniter is shown, having the usual 30 fixed and movable electrodes, the fixed electrode being insulated from the other parts. As this construction is well known, and as my improvement may be used with any 35 form of igniter, I will not describe same in detail, but describe only the auxiliary parts constituting my invention.

To the outer end of the movable contact stem 1 is attached a member 2 carrying a contact 3. To the fixed contact stem 4 is 40 attached the member 5 carrying the adjustable contact screw 6. A spring 7 is provided for locking this screw after adjustment. Piece 5 is kept from turning by the pin 8 surrounded by insulation 9, or 45 in any suitable manner.

One side of the source of current used with the igniter being connected to the flange carrying the movable electrode, and the other side to the nut 10 of the insulated 50 electrode, when the igniter is operated in the usual manner, a spark is produced between the firing contacts 11 and 12 of the fixed and movable electrodes, provided the screw 6 is so adjusted that it does not touch the contact 3. In fact the operation is as usual.

If in case of trouble, it is suspected that the firing contacts 11 and 12 are foul, or out of adjustment, it is only necessary to adjust screw 6 until it touches contact 3, 60 and if a spark results, it is evident that the circuit and source of energy are O. K., and the trouble is in the firing contacts, or their adjustment. Thus the condition of the firing contacts is readily determined without removing the igniter from the engine, 65 and without trouble or delay.

To test the source of current, it is only necessary to proceed as just described, the spark between the auxiliary contacts 6 and 70 3 indicating at once the condition of the battery or other source of energy employed. This is of particular advantage when an alternating current engine timed magneto is employed as with such a device the common expedient of disconnecting one of the battery wires and tapping it on the binding post and observing the spark, cannot be employed as the engine must be in motion to turn the magneto before any current is 75 available, and the break or tapping must take place exactly when the magneto is producing the peak of the current wave, otherwise no spark or a faint one will result, which is deceiving as to the true condition of the magneto.

In properly timing the igniter, the points 3 and 6 are brought together, and the screw 6 slowly backed off until no further spark results. It is now evident that the spark 80 is being produced at the firing contacts 11 and 12, and the timing can be observed and the igniter adjusted to a nicety by this method.

While I have shown but one form of 85 auxiliary contact, many other arrangements are obvious to those skilled in the art. I deem all such arrangements to be within one scope of my invention, which consists broadly of the combination with a make- 100 and-break igniter, of an external auxiliary contact.

I claim—

1. In an electric igniter having one fixed and one movable contact, an auxiliary contact movable with said movable firing contact and a fixed auxiliary contact electrically connected to said fixed firing contact. 105

2. In an electric igniter, a flange carrying a pair of make-and-break electrodes 110 with their firing points disposed on the inside of said flange and adapted to be in-

closed in an engine cylinder thereby, and a pair of auxiliary electrodes outside said flange operated in unison with said firing points and adjustable in relation to the opening and closing thereof.

3. In a make-and-break igniter, a flange, a fixed member supported thereby but insulated therefrom carrying contact points at opposite sides of said flange, a movable member in said flange carrying contact points at opposite sides of said flange, means

for adjusting the opening and closing of the contacts on one side of the flange relatively to the opening and closing of the remaining contacts, and means for locking 15 said adjustment.

In testimony whereof I hereunto affix my signature in the presence of two witnesses.

FRANK DREW WINKLEY.
